(57) CLAIM

The ornamental design for a shower drain hair catcher, as shown and described.

DESCRIPTION

FIG. 1 is a top perspective view of a shower drain hair catcher, showing my new design;

FIG. 2 is a bottom perspective view thereof;

FIG. 3 is a front elevational view thereof, the rear elevational view, left-side elevational view, and right-side elevational view all being identical thereto;

FIG. 4 is a top plan view thereof;

FIG. 5 is a bottom plan view thereof; and,

FIG. 6 is a cross-sectional view thereof, taken along line 6-6 of FIG. 4.

The broken lines in the figures depict portions of the shower drain hair catcher that form no part of the claimed design.
